METHOD OF FACING SLEEVES

Simon Touloumis, Troy, N. Y., assignor to Cluett, Peabody & Co., Inc., Troy, N. Y., a corporation of New York

Application September 20, 1943, Serial No. 503,081

4 Claims. (Cl. 2—121)

This invention relates to the manufacture of garments, for example, shirts, riding breeches, dresses, etc., and more particularly to a novel method of facing slit openings in such garments, such, for instance, as in the sleeve of a shirt, the lower portion of the leg of riding breeches, or the neck opening in the back of a dress.

It is customary, for example, to slit the sleeve of a shirt upwardly from the wrist to facilitate turning back the cuff, and the raw edges of the sleeve material resulting from such slitting are commonly faced with material similar to that of the sleeve proper. Ordinarily one facing is wider than the other, the wider facing overlapping the narrower facing when the cuff is buttoned.

In accordance with a practice customarily followed in making finer grades of shirts, the sleeve facings are made from strips of fabric cut to proper length and width and the operator stitches the facing material to the shirt material, then folds the facing material about the raw edge of the shirt material and again stitches the facing material to the shirt material. Two separate sewing operations with an intervening folding operation are thus necessary, and since the folding is done by hand, there is no certainty that the attached facing will be of uniform width from end to end, or that the facings of different shirts will be of the same width.

The principal object of the present invention is to provide a novel method of facing slit openings in garments, for example shirts sleeves, such as to insure substantial uniformity throughout the width of any individual facing, as well as uniformity of width of facings of different garments. This and other objects and advantages of the invention will be pointed out in the following more detailed description with specific application of the invention to a shirt sleeve by way of illustrative example but without limitation to shirts, and by reference to the accompanying drawings wherein.

Fig. 1 is a fragmentary view of the sleeve of a shirt or similar garment provided with facings in accordance with the present invention;

Fig. 2 is a view similar to Fig. 1 but with the cuff unbuttoned to show the inner facing strip;

Fig. 3 is a fragmentary view of the inner surface of the material used in making the sleeve, showing a slit extending lengthwise of the sleeve from its cuff end and whose opposite edges are designed to receive the respective facing elements;

Fig. 4 is a perspective view showing facing ma-

terial prepared in the form of a roll for use in the practice of the present invention;

Fig. 5 is a view similar to Fig. 3 but showing the narrow or inner facing strip applied to one margin of the slit in the sleeve material;

Fig. 6 is a diagrammatic section on the line 6—6 of Fig. 5;

Fig. 7 is a view similar to Fig. 5 but showing the opposite side of the sleeve material with the wider or outer facing strip attached to the opposite margin of the slit in the sleeve material;

Fig. 8 is a diagrammatic section on the line 8—8 of Fig. 7;

Fig. 9 is a view from the opposite side of the sleeve facing from that shown in Fig. 7;

Fig. 10 is a view similar to Fig. 9 but showing a further step in the operation; and

Fig. 11 is a view similar to Fig. 7 indicating the completion of the operation.

Referring to the drawings (Fig. 1), the numeral 1 designates a sleeve having a cuff 2. The sleeve has the outer facing member 3 extending inwardly from the cuff, and the button 4 for closing the cuff. Referring to Fig. 3, which shows a portion of the sleeve material before it is seamed together, the numeral 5 indicates a slit extending from the cuff end of the sleeve inwardly longitudinally of the sleeve. The slit has the margins 6 and 7 and at its inner end is bifurcated to define a triangular tongue 8 having the apex 9 and a base defined by an imaginary line connecting the points 10 and 11.

In accordance with the present invention, the facing material is preferably provided in long strips of uniform width which are preferably wound to form rolls S, as shown in Fig. 4. Strips 12 and 12^x (Fig. 8) of different widths are provided, strip 12 being a narrow or inner facing and the strip 12^x being the wider or outer facing strip. While it is preferred to provide this material in long lengths and to roll it for convenience in applying it, it is within the scope of the invention to provide the facing material in lengths each just sufficient to form one facing. Each facing strip is of a width enough greater than twice the width of the completed facing to provide for inturned hems at its edges.

In applying the facing strip 12 (Figs. 5 and 6), it is first doubled substantially along its center 13 to provide two plies 14 and 15 of equal width, and the edges 16 and 17 of these plies are turned inwardly to provide a hem finish. One margin, for example the margin 7, of the shirt sleeve material, is introduced (Fig. 6) between the inturned edges of these two plies of the facing.

55 A sewed seam 18 is then formed, the stitches

passing through the inturned edges and the margin of the shirt material. This seam extends the entire length of the slit 5, that is to say, as far as the point 10. Beyond this point the seam may be continued but without passing through the sleeve material, thus merely uniting the inturned edges 16 and 17 of the facing strip, the facing strip extending in the form of a tab (as shown at 19 in Fig. 5) a short distance beyond the base 10-11 of the triangle 8, for example, a distance approximating the width of the folded strip.

The other strip 12^x (Fig. 8) is likewise folded along its center line to form the fold 20 and plies 21 and 22, and the edges of these plies are turned in at 23 and 24 to form a hem finish. The opposite margin 6 of the sleeve material is introduced between the inturned edges 23 and 24 of the wider strip and is connected to the latter by a seam 25 which extends lengthwise of the slit 5 to the point 11, beyond which the seam merely connects the inturned edges 23 and 24 without passing through the shirt material. The wider strip 12^x thus extends in the form of a tab T beyond the base 10-11 of the tongue 8 to the point 19^x (Fig. 7), the length of this tab T between the point 19^x and the base of the tongue being approximately 1½ times the width of the folded strip.

In carrying out the above described folding, hemming sewing operations, it is convenient to perform these operations progressively by passing the strip material and the sleeve material through a suitable scroll type hemmer in a sewing machine, the work thus being doubled and hemmed and stitched together in a single operation. Since the facing material is of uniform width and is doubled before or during application, and since the edges which are thus turned in are of substantially equal width, the completed facing is of uniform width from end to end; likewise the facings of successively made shirts are of the same uniform width, thus providing a great improvement as compared with previous methods which have resulted in a great variation in the width of individual facings and in the widths of the facings of different shirts.

Having secured the two facings as described, the triangular tongue 8 is folded back along its base line to lie against the outer surface of the sleeve material, the narrow tab 19 is laid over the folded back tongue 8, and the wider tab T is laid over the tab 19 so as to conceal the latter. The corners 27 and 28 of the tab T are now turned in, as shown in Fig. 11, and a seam 29 is formed so as to border the parallel edges of this portion of the strip and to extend along the diagonal lines formed by turning in the corners 27 and 28. This seam is continued as shown at 30 so as to extend transversely across the strip the stitches extending through the material of both tabs, through the tongue and through the sleeve material, thus securing the tongue in its folded-in position. This procedure provides a much better and more finished appearance at the inside of the sleeve than results from usual prior practice, and furnishes a strong terminal construction for the inner end of the slit such as effectively to prevent ripping or tearing at this point.

While one desirable embodiment of the invention has been illustrated and described by way of example, it is to be understood that the invention is broadly inclusive of any and all modifications and substitutions of equivalent steps falling within the scope of the appended claims.

I claim:

1. That method of facing the edges of a slit shirt sleeve having a slit extending inwardly from its wrist end, the inner end of the slit being defined by a triangular tongue, which comprises as steps providing lengths of facing material, doubling each strip and turning in its edges, then inserting the opposite margins of the sleeve material between the doubled-in edges of the respective strips and sewing said edges and margins together, each strip being extended beyond the base of said triangular tongue a short distance to form free tabs each approximating the width of the respective folded strip, folding the triangular tongue back across the outer surface of the sleeve material, lapping one of the tabs over the folded tongue, lapping the other tab over the first tab, and forming a transverse seam substantially at the base of the tongue.

2. That method of facing the edge of a slit shirt sleeve having a slit extending inwardly from its wrist end, the inner end of the slit being defined by a triangular tongue, which comprises as steps providing two lengths of facing material, doubling and turning in the edges of each strip, introducing one margin of the shirt material between the turned-in edges of each of the respective strips and sewing said margins to the turned-in edges of the respective strips while causing the ends of the strips to extend, unconnected to said margins, beyond the base of the tongue a distance approximating the width of the respective folded strips to form free tabs, folding back the triangular tongue against the outer surface of the sleeve material, disposing the tab of the first applied strip over the folded tongue, disposing the tab of the other strip over the first tab, turning in the corners of the projecting end portion of the last-mentioned tab, and forming a seam bordering said last-mentioned tab, and uniting it and the tongue to the sleeve material, said seam extending transversely across both tabs at a point beyond the end of the slit.

3. That method of facing the edges of a slit garment part having a slit whose inner end is defined by a triangular tongue, said method comprising as steps providing lengths of ribbon-like facing material in two different widths, each length being sufficient to form a sleeve facing, doubling the narrower strip and turning in its edges, introducing one margin of the garment material between the turned in edges of said narrower facing strip and securing the margin and said turned in edges by a single sewed seam, the seam being continued beyond the end of the slit opening in such a way as to unite the turned in edges of the facing without passing through the sleeve material, thereby forming a tab of a length substantially equaling the width of the folded facing, doubling the wider strip and turning in its edges, introducing the other margin of the garment material between the turned in edges of the latter strip, securing said latter margin and turned in edges by a single sewed seam which is extended beyond the end of the slit opening in such a way as to unite the turned in edges of the facing without passing through the sleeve material, thereby forming a tab of a length which is substantially one and one-half times the width of the folded facing, folding the triangular tongue back along its base line so that it contacts the outer surface of the garment part, laying the tab of the narrower facing over the folded tongue, laying the tab of the wider facing over the tab of the narrower facing so as to conceal the latter, forming a sewed seam extending transversely

across the wider tab at a point beyond the end of the slit, the stitches of said seam passing through both tabs, the tongue and the garment part, turning in the corners of the tab of the wider strip, and uniting said tab to the sleeve material by a seam which borders the parallel edges of the wider tab and extends along the diagonal lines resultant from turning in the corners of the tab.

4. That method of facing the edges of a slit in a garment part which comprises as steps providing two strips of facing material each of substantially uniform width, but one wider than the other, each strip being of a length somewhat greater than the length of the slit, doubling the narrower strip, turning in its longitudinal edges, introducing one margin of the garment part between the turned-in edges of the facing strip and uniting the margin and said turned-in edges by a sewed seam which is continued beyond the end of the slit in such a way as to unite the edges of the facing without passing through the garment

material thereby forming a free two-ply tab of the facing material beyond the end of the slit, similarly doubling the wider strip, turning in its edges, introducing the other margin of the garment part between said turned-in edges of the wider strip, and uniting the latter margin and the edges of the strip by a sewed seam which is continued beyond the end of the slit in such a way as to unite the edges of the wider facing strip without passing through the garment part, thereby providing a free two-ply tab of the wider strip beyond the end of the slit, laying the narrower tab down against the outer surface of the garment part beyond the end of the slit, laying the wider tab down over the narrower tab so as to conceal the latter, forming a sewed seam extending transversely across both tabs and through the garment part at a point beyond the end of the slit, and uniting the free margins of the wider tab to the garment part by sewing stitches.
